INSULATION OF BUILDINGS

Harry D. Powell, Findlay, Ohio

Application April 26, 1939, Serial No. 270,140

2 Claims. (Cl. 20—4)

The general object of this invention is to provide water-proofed or vapor barrier in a chambered wall.

An angle of carrying out the objects of the invention is disclosed when incorporated in connection with building structures having inter-wall chambers by lining said chambers with inflatable water-proof walled receptacle or bag to fit into the chamber and hold such bag to form, with charge, resistant to heat conduction, of fire-proof fiber as of rock wool to fill the chamber body as a sealing partition.

My invention relates to improvements in the method of inserting insulating material into the spaces between the outside and inside surface covering of walls of houses and other buildings that have not been provided or filled with such insulation material in the process of original construction. It also relates to the improvements in the means and methods of producing by such insulation a moisture proof condition of the insulating material and of the spaces between the outside and inside covering or surface of such walls (to illustrate, as between an outside sheeted, brick, stucco or other outside covering and a plastered or other covered inside surface covering), and so preventing moisture from saturated atmosphere, storm or other source, by contact of the insulating material with the said wall coverings, passing through or causing condensation and moistening of the inside wall surface, resulting in the loosening of paper or other ornamentation thereto attached.

Also my invention relates to and accomplishes a more even and uniform density of the insulating material when inserted and in place in said wall spaces.

My invention is particularly for the purpose of use with rock or mineral wool, the ordinary material used for insulation, but it is adapted to the use of any finely divided material that may be used for insulating or similar purposes.

Referring to the drawing:

Fig. 1 is a vertical section of an inter-wall chamber as receiving a charge of collapsed lining therefor;

Fig. 2 is a view of the inter-wall chamber of Fig. 1, with the lining inflated in said chamber of the wall; and

Fig. 3 is a view of the inflated lining of the wall of Fig. 2, with said lining receiving a charge of insulating material as rock wool.

I accomplish the above stated objects of my invention by inserting in the spaces A to be filled between the two wall coverings, as divided by

5 studding or other partition, a moisture proof paper, or other interior smooth-surfaced, bag or receptacle B in a collapsed or flattened condition, but of dimensions when expanded to fit snugly and tightly the space to be filled with the insulating material. This receptacle B being so inserted in its collapsed form into the said space A is then expanded therein by the use of compressed air through pipe or hose H, so that it fits tightly around and against the several sides of the space to be filled and over such inequalities of surface as may there exist. The receptacle being thus fitted to its place, the air pressure is released and the insulating material C is inserted at its top in a uniform condition of density produced by previous division and aeration and fall freely through the smooth sided receptacle, by gravity, until the space required is filled.

10 The smooth sides of this receptacle allow the material to fall by its weight without friction against and obstruction by the otherwise rough and uneven wall coverings (lath, plaster, etc.). The space is thus filled with an even and predetermined density that ministers both to economy of operation, material and efficiency. The water-proofed container effectually prevents moisture from either entering the insulating material, and the insulating material within such water-proofed receptacle being dry and containing its evenly aerated dry spaces prevents moisture from passing to, or condensation forming on, the inside wall surface.

15 Where necessary, by reason of roughness or other obstructions, to insure the collapsed receptacle going down to the bottom of the space to be filled, I insert in the lower end of the receptacle either a permanent weight, or a weight W that may be recovered by an attached cord S when the receptacle is in place and expanded.

20 I have illustrated my said invention in the drawing hereto attached in which Fig. 1 is a cross section of an ordinary constructed wall space A and showing the outer and inner surface coverings, and extending down through such space the collapsed receptacle B extending from the sill or lower end of space A to its top, where in the drawing a piece of outside wall covering is removed to give access to the space to be filled, both for inserting the receptacle B and for filling the same when expanded.

25 Fig. 2 is same as Fig. 1 but with receptacle B expanded by the compressed air until it fits closely to the sides of the space in the wall to be filled.

30 Fig. 3 is the same cross section of wall as in

Figs. 1 and 2 with receptacle B expanded and insulating material C entering and partly filling receptacle B.

Having described my invention, and stated its object, what I claim as new is:

1. The method of insulating a building having an inter-wall chamber comprising the steps of establishing an entrance opening to said chamber, inserting through said opening a flexible wall water-proof container, projecting said container into said chamber away from the opening, and charging said container with insulating material and thereby effecting the isolation of said material from moisture laden air.

2. The method of effecting insulation of a 15

building having an inter-wall chamber comprising the steps of removing a portion of the wall of the building to form an entrance opening to an upper portion of the chamber, inserting through 5 said opening a deflated water-proof flexible wall container, distending said container into the chamber to extend away from the opening, inflating the container to an extent to be engaged and supported by the chamber sides, and charging the inflated container with mineral wool insulation to retain said distended and wall-held container as a water-proof barrier against moisture harboring or transmission.

H. D. POWELL.
